AMALGAMATING AND CONCENTRATING APPARATUS

Robert M. Coyle, Denver, Colo., assignor to The Coyle Mineral Extraction Corporation, a corporation of Colorado

Application February 18, 1929, Serial No. 340,754

12 Claims. (Cl. 269—437)

This invention relates to the recovery of values from comminuted material by amalgamation and/or concentration, and relates particularly to the recovery of such values on a vibrating 5 table by mercury amalgamation and/or by concentration, and has for an object to provide a device for such amalgamation and/or concentration which shall be simple and economical in construction and operation, compact, efficient 10 and durable.

A further object is to provide, in a mechanism of the class described, longitudinal vibrations to a transversely rifled table.

A further object is to provide an interrupted 15 vibrating movement for such table.

A further object is to provide a transversely rifled, longitudinally inclined amalgamating table with vibratory movement varying from 20 combined longitudinal and substantially vertical at the upper end to substantially longitudinal alone at the lower end and, in such a table, to provide means for substantially eliminating said vertical vibratory movement when desired.

A further object is to provide a table of the 25 class described which may be used for concentration alone, for amalgamation alone, and for amalgamation and concentration coincidently.

A further object is to provide means for subjecting the pulp in passage over such table, to 30 the action of electrical current.

With these and other objects in view, which will appear and be amplified in the following specification and be defined in appended claims, 35 the invention comprises certain novel constructions, combinations and arrangements of parts more fully described and claimed and illustrated in the drawings in which corresponding parts are indicated by like characters throughout and in which

Figure I is a side elevation of my amalgamator and concentrator with pulp feeder, with portions broken away and/or shown in section.

Figure II is a plan of the table partially covered, by the cathode cover in operative position over the upper portion of the table, portions being broken away.

Figure III is a section on line "A—A" of Figure I showing the vibrating mechanism in plan.

Figure IV is a fragmentary section on line "B—B" of Figure III.

Figure V is a fragmentary section on line "C—C" of Figure III.

Figure VI is a section on line "D—D" of Figure 55 II also showing feed distributor.

Figure VII is a section on line "E—E" of Figure VI.

Figure VIII is a section on line "F—F" of Figure VI.

Figure IX is an enlarged detail section of one 5 of the cathodes and its mounting.

Figure X is a detail of the vibration changing brace bar.

Figure XI is a fragmentary, illustrative view 10 of the under side of the cathode cover.

In practice an amalgamator and concentrator constructed in accordance with my invention and having an outside measurement of approximately 3 feet in height, 4 feet in length and 2 feet in width will have a capacity of approximately fifty tons or more of material in twenty-four hours and a total weight of approximately three hundred and fifty pounds.

For convenience a base 1 having castors 2 may be provided and the machine may be 20 mounted thereon as clearly shown in Fig. I so that it may be moved from place to place as desired.

Uprights 3 carry a support 4 for motor generator unit 5 and said uprights likewise carry 25 a frame 6 on which are supported, through vibration absorbing means as springs 7 and 8, the table 9 and the vibrating unit, clearly shown in Fig. III, the structure of the table and the vibrating unit as well as the resilient inter- 30 connections therebetween being hereinafter more fully described.

The table 9 has a rifled floor 9a which is preferably made in removable sections. Whenever 35 electrical current is to be applied to the pulp, as hereinafter described, the rifled floor is made of water proof, acid proof, insulating material such as rubber or "bakelite." The table 9 is provided with sides 9b, (thus forming, in effect, a transversely rifled, flatbottomed trough) and 40 end piece 9c, troughs 10 and 11 being formed in the bottom of the table respectively at the upper and lower ends of the rifled, flat bottom trough.

The table is provided with rests 9d which may 45 be extensions of one of the cross members 13 hereinafter described which rests 9d rest upon springs 7 whereby the lower end of the table is resiliently supported from frame 6. The table is provided with hollow longitudinal stiffening 50 and vibration distributing ribs 12 formed rigidly with the bottom of the table and therebeneath.

Cross members 13 of angle iron are rigidly mounted on the bottoms of the ribs 12 and to these cross members are rigidly attached the 55

arms of rigid Y plates 14 and 15, the stems of which are attached to resilient cross members 22 and 23 for forming the resilient inter-connection between the table above described and the 5 vibrating unit which will now be described.

The vibrating unit is clearly illustrated in Fig. III and consists of a U member 16 pivotally and resiliently suspended from the frame 6 by suitable means as goose-necks 17 bearing in toggle yokes 18, the toggle yokes being in turn suspended by nuts 19 on lower ends of bolts 20 carrying nuts 21 at their upper ends and being supported on the frame 6 by coil springs 8 encircling the bolts 20.

15 The sides of U member 16 are somewhat shorter than the table 9 so that when the base of the U is positioned beneath one end of the table the side arms will extend to a point beneath the other end portion of the table 9, but preferably a little short 20 of the end of the table as clearly shown in Figs. I and III.

25 For forming resilient inter-connection and mutual supporting means between the table 9 and the vibrating unit, two resilient cross members 22 and 23 are provided between the side arms of the U. These resilient cross members are preferably formed of spring leaves rigidly affixed at their ends to the side bars of the U 16 the resilient member 22 being preferably, and member 23 30 may be if desired, formed of a plurality of said spring leaves with intervening spacers 24.

35 The preferable construction of the side arms for the mounting of said resilient cross members is clearly illustrated in Figs. I and III and consists of forming the side arms in sections 25 and 26 and providing on the ends of said sections suitable flanges 27 for bolting the cross member 22 therebetween and for bolting the cross member 23 thereto.

40 The stems of the Y plates 14 and 15 are affixed to the resilient cross members 22 and 23 and near the central portion of each of the cross members by suitable means as bolts 28 whereby a resilient interconnection is provided between the table 9 and the U member 16.

45 Suitable means are provided for imparting a vibration to the table 9 through the cross member 22 and such means preferably consist of an electromagnet 29 rigidly mounted on the base 50 of the U member 16 as by bolts 30 and having a keeper 31 affixed to the cross member 22.

55 When alternating current is passed through magnet 29, the keeper 31, the central portion of the cross member 22, the Y 14 and thereby also the table 9, Y 15 and central portion of the cross member 23 will all be instantaneously retracted to and held by the magnet 29 by the positive semicycle, thereafter the keeper 31 is released during the negative semicycle of the current and the resilience of the cross members 22 and 23, acting 60 through the Y's 14 and 15, moves the table 9 forward whereupon the next positive semicycle of current again retracts the table and so on.

65 The retraction of the table by the action of the current is quicker than the forward movement of the table caused by the resilience of the cross members 22 and 23 wherefrom it is obvious that the table is given an interrupted or irregular longitudinal vibration, the retracted 70 or backward movement being practically instantaneous while the forward movement is slow in comparison with said backward movement.

75 The nature of the vibration thus imparted to table 9 and its effect upon the material passing over the table and the part which the said vi-

bration plays in the operation of the present apparatus and process will be hereinafter more particularly described.

It will be understood that various mechanical movements operated by any suitable motive power may be employed in place of the magnet 29 and keeper 31 for imparting longitudinal vibration and for varying the length thereof, but the magnet and keeper are preferable for various reasons, and particularly where the hereinafter described process, involving the application of electrical current to the pulp in its passage over the table, is employed.

In such case, electrical apparatus being necessary for the provision of such current, it is 15 economical and convenient to use the magnet and keeper for providing such vibration. The length of longitudinal vibrating movement may be varied by varying the normal magnetic flux and by distortion of the alternating current in 20 well known ways. This movement will ordinarily be approximately three thirty seconds of an inch.

Under certain conditions it may be desirable to cause the table to vibrate only longitudinally and in such case the vibration changing brace 25 bar, shown at Fig. X is employed to rigidly couple the resilient members 22 and 23 as indicated in dotted lines at Fig. III. When thus coupled the central portion of member 23 will be directly distorted by the retraction of keeper 30 31 and member 22 and this will result in a simple longitudinal vibration of the table.

When the brace bar X is not used member 23 acts as a drag and tends to retard the movement of the table toward its higher end. This retarding tendency combined with the cantilever mounting of the combined table and vibrating unit and the resilient supports results in a double or combination vibration of the upper end of the table which is given a substantially vertical 40 vibration as well as the longitudinal vibration. These two vibratory movements resolve themselves into a single, circulatory movement of the upper portion of the table, which in turn imparts a circulatory or revolving motion to the 45 contents of the riffles, thus facilitating amalgamation and the raising and washing away of any gangue matter caught in the upper or amalgamating riffles.

50 The vertical vibration decreases toward the lower end of the table so that the lower portion of the table has practically only the longitudinal vibration.

When dry material is to be concentrated on the table it may be fed thereto in any suitable manner, well understood, but, when pulp is to be treated for properly mixing and efficiently feeding the pulp to the table, I provide a hopper 32 suitably supported by a framework 33 with a conduit 34 leading from the bottom of the hopper to the feed distributor 35, a water supply pipe 36, with control valve 37, being provided and positioned to supply water approximately at the junction of the hopper and the conduit for mixing the water with the material as it passes from the hopper into the conduit. Baffles 38 are provided in the conduit for facilitating the mixing of the water and the material.

55 Pipe 36 is preferably positioned so as to shoot a stream into the conduit 34 whereby to suck the material from the hopper into the conduit and, in combination with the impedance of the baffles 38, to effect a thorough mixing of the water and material to form a pulp of the desired 60 fluidity.

The feed distributor 35 is clearly illustrated in Figs. VI and VIII and consists of a nozzle, pear shaped in section, but elongated transversely of the table and of a length approximately the 5 width of the table and being so contracted at its lower extremity as to provide a narrow aperture 39 through which a sheet of pulp will be projected downwardly out of said distributor into the trough 10 for substantially the full width of 10 the table 9.

While pulp is being thus supplied to the table, drainage through the bottom of trough 10 is prevented by any suitable plugging of the passage 10a as by a rod inserted therein or a plug in 15 the end thereof.

It will be understood that the table 9 is mounted at an incline downwardly from the end to which the pulp is supplied which inclination is obtained by the relative variation in length 20 of the springs 7 and 8, including the adjustment of the nuts on bolts 20.

While it is not absolutely essential that the trough 10 be positioned beneath the outlet 39 of the distributor 35 it is preferably so positioned 25 in order that the pulp may be projected from the distributor into a mass of pulp in the trough 10 whereby the same is kept in agitation and sliming is prevented.

The pulp flows from the trough 10 down over 30 the riffled floor and its flow is alternately interrupted and facilitated by the irregular vibration of the table as above described.

While the table may be used solely for concentration of both wet pulp and dry material, its 35 most desirable use is for combined amalgamation and concentration and when thus used the upper riffles, for preferably from one-third to one-half of the length of the table, are filled with mercury for amalgamating metallic particles which are separated from the gangue.

It will frequently be found desirable to provide a form of riffle for the amalgamating section of the table different from the form of riffle provided for the concentrating section. 45 This difference in form is clearly illustrated in Figs. I and VI, but it is not intended to indicate thereby any particular form of riffle as the form of riffles for both sections of the table may be varied to suit the requirements of any ore being 50 treated.

The general principles of amalgamation of values from ore pulp are well understood and it has been found in practice that the above described vibratory movement of the amalgamating 55 portion of the table during the passage of the pulp thereover, combined with the transverse arrangement of the riffles, gives a very efficient action.

The material is caused to rotate in the amalgamating riffles, thus aiding in bringing any retained gangue to the top of the riffle where it will be washed away, leaving the heavier particles in the riffle with the mercury. The concentration takes place primarily in the lower riffles 65 and then in the trough 11. The concentrates partially fill the trough 11 and the tailings pass thereover and flow off the lower end of the table. The concentrates in the trough 11 work down into the passage 11a from which they are 70 drained off into any suitable receptacle.

To aid in the amalgamation of the separated metallic particles, as well as to cleanse the metallic particles which do not amalgamate, I provide a process and apparatus now to be described. 75

In amalgamation an impediment frequently is the coating of separated metallic particles as by oxidation thereof. The prevention or removal of such coating will facilitate the amalgamation. The cleansing of particles to be concentrated will likewise facilitate the subsequent treatment of the concentrates.

The present process and apparatus is designed to prevent and to remove any coating of the metallic particles and for this purpose I provide 10 a cover 40 carrying supporting straps 41 mounted at their outer ends between adjusting nuts 42 and on threaded supports 43 mounted on the sides 9b of the table whereby the height of the cover 40 above the bed of the table may 15 be adjusted as desired. Cathodes 44 are carried on the underside of the cover projecting downwardly therefrom toward the amalgamating riffles.

The cover 40 is formed of a plurality of layers, 20 the bottom layer 40a being of suitable conducting material and connecting, and thus conducting the current to, cathodes 44 from the terminal 45 suitably connected with the generating unit 5 by cable or conductor not shown. The 25 balance of the cover 40 is of suitable non-conducting material.

As previously stated, the riffled floor of the table is formed of water proof, acid proof, insulating material. Suitable grounds are provided by the fastening screws 46 which secure 30 the riffles 9a to the metallic bottom 9e of the table.

When the amalgamating riffles are filled with mercury and the pulp is flowed thereover to the 35 desired depth, the cover 40 is so adjusted in height that the lower edges of the cathodes 44 will contact with the flowing pulp whereby the current supplied to the anodes will pass therefrom through the pulp to the mercury in the 40 riffles and thence to the grounds.

The pulp is rendered saline by supplying salt to the water forming the pulp and as such pulp is subjected to the current passing from the anodes to the mercury, chlorine is released 45 therein by the action of the electric current upon the salt resulting in a weak chlorine solution in the pulp, and this solution cleanses the separated metallic particles and thus facilitates the amalgamation of some and cleanses those passing 50 into the concentrates. The chlorine solution is restricted to a strength sufficient only to accomplish the cleansing of the particles.

When it is desired to clean the riffles the lower end of the table may be lifted sufficiently 55 to cause the contents of the riffles to flow over the floor into the trough 10 and thence through the passage 10a into a suitable receptacle, water being used to facilitate the cleansing of the riffles as necessary.

While ore and pulp have been referred to in the foregoing specification, it will be understood that placer sands and any other fine material containing metallic particles may be treated by the apparatus and in accordance with the process hereinabove described, and that dry concentration may be accomplished by the apparatus as well as concentration of values from pulp. 65

Also, it will be understood that the passage 70 of the electrical current through pulp, even without any salt in the pulp, will aid in precipitation of metallic particles and thus aid amalgamation and/or concentration by reason of the conductivity of the mineral particles in pulp 75

material and the native salts, alkalis or acids present in most pulp material.

As the table and vibrating unit are interconnected, as hereinabove described, it is obvious that the raising or lowering of the vibrating unit will raise or lower the table and therefore the inclination of the table may be changed at any time, even during operation, by adjustment of the nuts 21 up or down on bolts 20. 10 This adjustment of inclination of the table during operation is very useful, especially in experimental work on new or untried ores and the like.

It will also be understood that many changes 15 may be made in detail of construction within the spirit and scope of the invention and of the appended claims.

The construction of the riffles as clearly shown at 9a in Figs. I and VI, is an important element 20 in the successful operation of the apparatus and from inspection of the said figures it will be noted that the riffles are formed with the lower side of each riffle rising upwardly from and substantially perpendicular to the plane of the bed 25 of the table, while the upper side of the riffle is inclined in the same general direction as the bed of the table but at a greater degree than the degree of inclination of said bed. This form of riffle cooperates with the particular form of 30 vibration imparted to the table and to the pulp thereupon, as hereinabove described, and renders the operation more effective in accomplishing the separation, concentration and/or amalgamation of the values from the pulp.

35 I claim:

1. In apparatus of the class described, a frame, a table and means for imparting vibrations to the table, one end of said table being resiliently supported on the frame and the other 40 end of said table being resiliently supported on said means, which means are resiliently supported on the frame, said means comprising a vibrating unit having side bars, a resilient cross member between said side bars and having rigid 45 interconnection with the upper portion of the table, a second resilient cross member between said side bars and having rigid interconnection with the lower portion of said table and means for distorting said first cross member and then 50 releasing the same whereby when said first member is thus distorted the table is moved toward its higher end and said second cross member is also distorted and when said first cross member is released the return to normal position 55 of said two cross members moves the table toward its lower end, the combined vibrating means and table being resiliently supported on the frame.

2. In apparatus of the class described, a frame, a table and means for imparting vibrations to the table, one end of said table being resiliently supported on the frame and the other end of said table being resiliently supported on 60 said means, which means are resiliently supported on the frame, said means comprising a vibrating unit having side bars, a resilient cross member between said side bars and having rigid 65 interconnection with the upper portion of the table, a second resilient cross member between said side bars and having rigid interconnection with the lower portion of said table and means for jerking said first cross member and then releasing the same whereby when said first member is thus jerked the table 70 is jerked toward its higher end and said second

cross member is also distorted and when said first cross member is released the return to normal position of said two cross members moves the table toward its lower end, the combined vibrating means and table being resiliently supported on the frame. 5

3. In apparatus of the class described, a frame, a rifled table, a vibratory unit, resilient interconnection between the table and the unit, the combined table and unit being resiliently supported at one end by the frame and, at the other end, being pivotally and resiliently supported by the frame whereby said table is normally higher at said pivotally supported end, but the opposite end may be lifted above said 10 pivoted end for emptying said riffles. 15

4. In apparatus of the class described a frame, a table and means for imparting vibrations to the table, one end of said table being resiliently supported on the frame and the other end of 20 said table being resiliently supported on said means, said means being resiliently supported on said frame.

5. In apparatus of the class described a frame, a rigid table and means for imparting vibrations to the table, one end of said table being resiliently supported on the frame and the other end of 25 said table being resiliently supported on said means, said means being resiliently supported on said frame. 30

6. In apparatus of the class described a frame, a table and means for imparting vibrations to the table, one end of said table being resiliently supported on the frame and the other end of 35 said table being resiliently supported on said means, said means being resiliently supported on said frame and means to vary the inclination of the table. 40

7. In apparatus of the class described a frame, a table and means for imparting vibrations to 45 the table, one end of said table being resiliently supported on the frame and the other end of said table being resiliently supported on said means, said means being resiliently supported on said frame, interconnection between the table and said means comprising rigid members and resilient members unconnected with the frame, means for jerkily distorting said resilient members in one direction only and thereafter releasing the same whereby to jerk said table in 50 one direction longitudinally by said distorting means and to move the table in the opposite direction longitudinally by means of and with the return to normal position of said resilient members. 55

8. In apparatus of the class described a frame, a table and means for imparting vibrations to the table, one end of said table being resiliently supported on the frame and the other end of 60 said table being resiliently supported on said means, said means being resiliently supported on said frame, said means carrying resilient members unconnected with the frame and means for distorting said resilient members in one direction only and thereafter releasing the 65 same, and rigid interconnection between the table and the resilient members, whereby to move the table longitudinally and with said resilient members as they are distorted from and returned to their normal position. 70

9. In apparatus of the class described a frame, a table and means for imparting vibrations to the table, one end of said table being resiliently supported on the frame and the other end of 75 said table being resiliently supported on said

means, said means being resiliently supported on said frame, said means including a plurality of resilient members, each having rigid connection with the table.

- 5 10. In apparatus of the class described a frame, a table and means for imparting vibrations to the table, one end of said table being resiliently supported on the frame and the other end of said table being resiliently supported on said means, said means being resiliently supported on said frame, said table having transverse ripples having their lower sides rising upwardly from, and substantially perpendicular to, the plane of the bed of the table and having
- 10 15 their upper sides inclined in the same general direction as the inclination of the bed of the table but at a greater degree of inclination.
11. In apparatus of the class described a frame, a table and means for imparting vibra-

tions to the table, said table and said means comprising a unitary structure resiliently supported on the frame by vertically resilient interconnection between the frame and the table at one end of said structure and by vertically resilient interconnection between the frame and the vibration imparting means at the other end of said structure.

12. In apparatus of the class described, a frame, a table and means for imparting vibrations to the table, said table and said means being resiliently interconnected and comprising a unitary structure resiliently supported on the frame by resilient interconnection between the frame and the table at one end of said unitary structure and resilient interconnection between the frame and the vibration-imparting means at the other end of said unitary structure.

ROBERT M. COYLE.
